TRAILER HITCH FRAME BRACKET

Gerald L. Bock and Charles Weber, both of
2132 S. Main St., Elkhart, Ind. 62634

Filed Apr. 3, 1967, Ser. No. 6,502

Term of patent 14 years

Int. Cl. D12—14

U.S. Cl. D14—6

FIG. 1

FIG. 6

FIG. 2

FIG. 3

FIG. 4

FIG. 5

FIGURE 1 is a side elevational view of a trailer hitch frame bracket embodying the present design and showing the frame bracket mounted on a trailer frame and connected with a trailer hitch member by a chain;

FIGURE 2 is a front elevational view of the frame bracket the upper portion of the rear element being broken away for convenience of illustration only;

FIGURE 3 is a top plan view of the present frame bracket;

FIGURE 4 is a rear elevational view;

FIGURE 5 is a vertical cross-sectional view taken on line 5—5 of FIGURE 1; and

FIGURE 6 is a vertical cross-sectional view taken on line 6—6 of FIGURE 3.

The chain and frame member shown in broken lines in FIGURES 1 and 6 are included only for illustrative purposes.

We claim:

The ornamental design for a trailer hitch frame bracket, substantially as shown and described.
